UNITED STATES PATENT OFFICE.

SAMUEL H. MARTIN AND WILLIAM H. JONES, OF LINCOLN, ILLINOIS.

OPEN-FIREPLACE WATER-HEATING APPARATUS.

SPECIFICATION forming part of Letters Patent No. 541,867, dated July 2, 1895.

Application filed March 31, 1894. Serial No. 505,883. (No model.)

To all whom it may concern:

Be it known that we, SAMUEL H. MARTIN and WILLIAM H. JONES, citizens of the United States, residing at Lincoln, in the county of Logan and State of Illinois, have invented a new and useful Open-Fireplace Water-Heating Apparatus, of which the following is a specification.

This invention relates to open fire-place water heating apparatus; and it has for its object to effect certain improvements in open fire-places whereby the heat generated on the grate therein shall be more completely utilized than heretofore.

To this end the main and primary object of the present invention is to provide a new and useful fire back or lining for open fire-places in connection with several other features of construction whereby the fire-places shall be utilized for the heating of a building by either steam or hot water circulation.

With these and other objects in view which will readily appear as the nature of the invention is better understood, the same consists in the novel construction, combination and arrangement of parts hereinafter more fully described, illustrated and claimed.

In the accompanying drawings, Figure 1 is a front elevation of an open fireplace equipped with the herein-described improvements, showing the sliding air-tight front door dropped to its lowest position, and showing in dotted lines the position of the door when closed. Fig. 2 is a similar view on a small scale showing the air-tight front door adjusted to a position to bank the fire and to provide for the ventilation of the room. Fig. 3 is an enlarged vertical sectional view of the fireplace. Fig. 4 is a horizontal sectional view on the line $x-x$ of Fig. 3. Fig. 5 is a similar view on the line $y-y$ of Fig. 3. Fig. 6 is a detail plan view of the fire-grate. Fig. 7 is a detail view showing more clearly the connection of the connecting basins. Fig. 8 is a perspective view of the heating apparatus removed from the fireplace.

Referring to the accompanying drawings, 1 designates an ordinary open fire place formed in the wall of a building in the usual manner and from the top of which leads the ordinary chimney flue 2. The open fire place 1, is provided with the ordinary equipment

at the front of the wall, and in the present invention the inner side and back walls of the fireplace are adapted to be faced with the sheet metal lining 3, that conforms to the interior configuration or contour of the fireplace and extends to the front edges of the front opening of the fireplace, and said sheet metal lining 3 is provided at the top with the flue opening 4, that opens into the chimney flue 2. This lining 3, may be properly termed the outside lining of the fireplace attachments as it is intended to more thoroughly confine the heat and protect the interior heater devices that form the main fire back or lining for the fireplace.

At the usual point where the grate is located, the open fireplace accommodates therein the fire grate 5. The fire grate 5 preferably and essentially consists of the outer rectangular grate section 6, provided with a central opening 7, and a central dumping grate section 8, that is adapted to work inside of the opening 7 of the section 6.

The central dumping grate section 8 that works inside of the grate section 6 is mounted at its opposite ends on the usual journals 10.

The back and side walls of the open fireplace are lined with a series of vertical heating tubes 14 and 14^a, respectively. The vertical heating tubes 14 and 14^a, are arranged reasonably close together at the sides and back of the fireplace to form the side and back walls thereof directly next to the grate, which is enclosed in the space confined between the lower ends of the side and back series of these vertical heating tubes, in contact with which the heat from the fire directly comes in order to secure a thorough and rapid heating of the water that circulates therein. The said vertical heating tubes 14 and 14^a, are constructed in a substantially triangular shape in order to present the greatest possible surface to the heat, and at their front sides are provided with the longitudinal heat grooves 15, and at their corresponding rear sides with the vertical or longitudinal pipe grooves 16, the function of which latter grooves will be more particularly referred to, but it will be obvious that the front grooves 15 of the heating tubes greatly increase the heating area thereof. The back series of vertical heating tubes 14 are shorter than the side series of tubes 14^a,

or those located at opposite sides of the fireplace, and have projected from their upper ends the forwardly and upwardly disposed crown portions or crown tubes 17, that extend 5 directly over the fire so as to interrupt the direct upper passage of the heat and thereby secure a greater utilization thereof.

The upper extremities of the forwardly and upwardly disposed crown tubes 17 have connected thereto the lower ends of a series of short connecting pipes 18, the upper ends of which lead into the bottom of a hot water box or reservoir 19. The hot water box or reservoir 19, is arranged within the open fireplace 15 at the top thereof, and at one side of the chimney flue, and has connected thereto the flow pipes 20, that are designed to carry hot water or steam to the radiators arranged throughout the house.

20 The side series of vertical heating tubes 14^a, extend to points slightly above the inclined crown portions or tubes 17, and are connected at their upper ends to opposite ends of the inclined heating box 21 and the longest 25 of the tubes 14^a are connected at their upper ends to the box or reservoir 19, as clearly illustrated in Fig. 8 of the drawings. The inclined heating box 21, is arranged directly over the top of the crown tubes 17, and receives 30 the heating effect from the heat that passes between the said crown tubes, and also serves as a deflector to deflect the heat forwardly and upwardly before it can escape out of the chimney flue. The said inclined heating box 21, is entirely inclosed to confine the circulating water which runs therein from the side tubes 14^a, and has connected to the closed upper end thereof a series of connecting pipes 22, the upper ends of which connect with the 35 rear sides of the hot water box or reservoir 19.

The front heat grooves 15, of all of the vertical heating tubes extend the full length thereof, and in the back series of heating tubes 14 these grooves are continued through- 45 out the length of the crown portions or tubes 17, so as to secure the heating effect of the heat to the greatest possible extent in order that there may be no waste heat, and the longitudinal pipe grooves 16 at the rear sides of 50 the heating tubes are adapted to accommodate therein one side of the vertical feed pipes 23, and the upper ends of said feed pipes are coupled into the lower sides of the rectangular water ring 24, that encircles the inside of 55 the fireplace at an intermediate point and has connected to the opposite front ends thereof the upper ends of the return pipes 25, to which pipes 25 are coupled the return circulating pipes 26, that return the water or 60 steam from the radiators into the return pipes 25, that are arranged vertically at opposite front sides of the open fireplace.

The feed water which enters the return pipes 25, the rectangular water ring 24 and 65 the feed pipes 23, is necessarily subjected to the heating action of the fire within the fire-

place before reaching the vertical heating tubes, and the lower ends of the vertical feed pipes 23, alongside of the vertical heating tubes, are coupled to the lower ends of said tubes by the connecting basins 27. The basins 27 are connected directly to the lower ends of the pipes 23 and to the lower ends of the tubes 14 and 14^a, by means of the small coupling or connecting nipples 28, that prevent the cold or feed water from entering the heating tubes as rapidly as the hot water passes from said tubes into the box or reservoir 19, thereby causing a forced circulation or suction in the return pipes, whereby rooms 80 on the same floor as the open fireplace or grate may be heated as successfully as rooms above the same. The said basins 27, are each provided with bottom pet or drain cocks 29, for draining the heating tubes of sediment, 85 &c., at any time desired.

In order to increase the circulation of water or steam and to provide for a more complete utilization thereof a series of partitioned drop tubes 30 are connected at their upper ends to 90 the bottom of the hot water box or reservoir 19 by means of separate nipples 31, the water entering the tubes through one of these nipples and circulating out of the same through the other nipple, and in order to properly 95 control the draft of heat and to direct the same to different parts of the apparatus a regulator damper 32, is pivotally mounted within the open fireplace directly within the lower end of the chimney flue 2. By turning 100 this damper to one side or the other of the chimney flue, it will be obvious that the heat will be caused to circulate either throughout the front or rear portion of the fireplace heater just described, and which forms a fire back 105 or water lining for the grate.

In connection with the fire back heating apparatus is employed a sliding air-tight front door 33. The front door 33 is made of a single piece of sheet metal and is arranged 110 to slide at its opposite edges in suitable guides 34, at opposite front sides of the fireplace, and said door is of a size sufficient to entirely inclose the front opening of the fireplace and to be lowered into the ashpit 115 when not needed. The said front door 33 is provided near its lower edge with a series of draft openings 35, that are adapted to be brought into a position below the grate for supplying the same with a draft when the 120 door is lifted, and this door is provided with two sets or series of these openings, in one set or series of which there is a less number of openings to provide for the banking of the fire at night as shown in Fig. 2 of the drawings. Opposite weight chains 36, are connected at one end to opposite top edges of the door 33 and passing over suitably arranged guide pulleys 37, are connected at the other ends to balancing weights 38, working within 130 opposite inner sides of the fireplace to provide for balancing the door. By lowering the

door entirely below the grate line the fireplace may be used in the ordinary manner as shown in Fig. 1.

By adjusting the door to the position shown 5 in Fig. 2, the fire is banked by cutting off the direct and main draft while a top ventilating opening α , is left to allow impure air to pass out into the chimney, and by closing the door as shown in dotted lines in Fig. 1, the direct 10 draft is given to the fire, and the door then acts as a blower, thereby transforming the open fireplace substantially into a furnace 15 heater, and confining all the heat onto the heating apparatus that forms the fire back or lining for the fireplace.

Changes in the form, proportion and the minor details of construction may be resorted to without departing from the principle or sacrificing any of the advantages of this invention.

Having thus described the invention, what is claimed, and desired to be secured by Letters Patent, is—

1. In a heater of the class described, a series of upright heating tubes adapted to be arranged within an open fireplace, a hot water box or reservoir adapted to be arranged within the top of an open fireplace and connected with the upper ends of said tubes, a rectangular water ring adapted to encircle said tubes and connected with the lower ends thereof, and return pipe connections with said water ring, substantially as set forth.

2. In a heater of the class described, the upright triangularly shaped heating tubes adapted to be arranged within an open fireplace and provided at their front and rear sides with longitudinal grooves, and circulating pipe connections with said tubes certain 40 of said pipe connections being arranged in the rear grooves of said tubes, substantially as set forth.

3. In a heater of the class described, a series of vertical heating tubes adapted to be arranged at the back of an open fireplace and provided with forwardly and upwardly disposed crown portions or tubes an inclined heating box arranged over said crown portions or tubes, and circulating connections 50 with the upper and lower ends of said heating tubes certain of which tubes are connected to said heating box, substantially as set forth.

4. In a heater of the class described, a series of upright heating tubes adapted to be 55 arranged at the sides and back of an open

fireplace, the back series of tubes being provided with forwardly and upwardly disposed crown portions, an inclined heating box arranged directly over the top of said tube crown portions and connected at its opposite ends 60 with the side series of heating tubes, a hot water box or reservoir, connections between the upper ends of the tube crown portions and the heating box and said hot water box or reservoir, and return pipe connections with the 65 lower ends of the said heating tubes, substantially as set forth.

5. In a heater of the class described, a series of upright heating tubes adapted to be arranged within an open fire place and provided at the rear sides with longitudinal pipe grooves, flow connections with the upper ends of said tubes, a rectangular water ring adapted to be arranged within the fireplace and embracing said tubes, a series of vertical feed 70 pipes connected to said water ring at their upper ends and at their lower ends to the lower ends of said heating tubes, said vertical feed pipes being arranged in the pipe grooves of the heating tubes, and return pipe connections with the opposite front ends of said water ring, substantially as set forth.

6. In a heater of the class described, the combination with the heating tubes adapted to be arranged around a grate and having 85 flow connections with their upper ends, the feed pipes arranged at one side of the heating tubes, connecting basins connected to the lower ends of said feed pipes, and small coupling or connecting nipples connecting said 90 basins with the lower ends of said heating tubes, substantially as set forth.

7. In a heater of the class described, the combination of a hot water box or reservoir adapted to be arranged within the top of an 95 open fireplace the heating tubes connected therewith; a separate heating box connected with certain of said tubes, and a series of partitioned drop tubes connected by separate connections with the bottom of said hot water box or reservoir, substantially as set forth.

In testimony that we claim the foregoing as our own we have hereto affixed our signatures in the presence of two witnesses.
